UNITED STATES PATENT OFFICE.

PHILIP C. ARNOLD, OF EAST HAMPTON, CONNECTICUT, ASSIGNOR TO THE BEVIN BROTHERS MANUFACTURING COMPANY, OF SAME PLACE.

BICYCLE-BELL.

SPECIFICATION forming part of Letters Patent No. 577,408, dated February 23, 1897.

Application filed December 23, 1896. Serial No. 616,817. (No model.)

To all whom it may concern:

Be it known that I, PHILIP C. ARNOLD, a citizen of the United States, and a resident of East Hampton, in the county of Middlesex and State of Connecticut, have invented certain new and useful Improvements in Bells, of which the following is a full, clear, and exact description, whereby any one skilled in the art can make and use the same.

10 The object of my invention is to provide a bell with striking mechanism which shall be simple, effective, and compact in construction and by the use of which the bell may be sounded by a slight pressure upon the operating-lever handle sufficient to cause the

15 striker-arm to move.

A further object is to provide a bell having striking mechanism adapted to strike frequent repeated blows with certainty and clearness.

To this end my invention consists of the several parts and in the combination of such parts, as hereinafter described, and set out in the claims.

25 Referring to the drawings, Figure 1 is a plan view of the base of the bell, showing the striker mechanism. Fig. 2 is a view in vertical section through the base and the gong, showing the striker mechanism in side elevation. Fig. 3 is a view in side elevation of the striker-bar with part cut away to show construction of the striker. Fig. 4 is a bottom plan view of the striker-bar. Fig. 5 is a detail view in cross-section of the striker, on enlarged scale, as shown by the dotted outline x of Fig. 4. Fig. 6 is a top view of the carrier-plate. Fig. 7 is a detail edge view. Fig. 8 is a plan view of the striker-bar. Fig. 9 is an edge view of the same.

40 In the accompanying drawings my invention is shown embodied in a bell which is particularly adapted for use on a bicycle, although the invention is easily applicable to striking mechanism in bells adapted for other uses.

45 In the drawings, the letter a denotes the base of the bell, preferably cup-shaped and supporting the striker mechanism. In the center of the plate a post b serves as a support and means for attachment of the gong c . The under surface of the base is provided with a clamp d for fastening the bell to the

handle-bar or other convenient part of the bicycle.

The lever e is pivoted to the base a , with 55 the end e' projecting and forming a thumb-piece, the inner end of the lever being provided with a curved rack e^2 , the teeth of which engage a pinion f or arbor which supports the gear-wheel g . This gear-wheel g meshes 60 with a pinion h , which is mounted on the central post b and is free to rotate thereon.

The above-described features of the bell are of ordinary construction in bell mechanism, the special feature of my invention residing in the combination of the striker-arm and the supported strikers.

The striker-arm i is mounted on the central post and secured to the pinion, with which it revolves. It extends on both sides of the central post, preferably in line of a diameter, and supports a carrier-plate k , which is mounted on the upper surface of the striker-arm and has a limited lengthwise sliding movement thereon. Shoulders or stops limiting the extent of sliding movement of the carrier-plate on the striker-arm are preferably formed by making an opening k' through the substance of the carrier-plate and near its outer ends, a narrow portion upturned on the end of the 75 striker-arm forming stops i' on the opposite ends, and these stops extend through the slots k' and coöperate with its end walls in limiting the movement of the carrier-plate.

Strikers l are loosely pivoted on the outer 85 ends of the carrier-plate and on the pivots l' , the tapered front end of each striker projecting beyond the outer end of the carrier-plate. In each of the strikers a slot m is formed, and a stop, as i' , extends upward into this slot, so 90 as to limit the swinging movement of each striker on its pivot. The slot is of sufficient width to permit the lengthwise sliding movement of the carrier-plate on the striker-arm and is of a length to provide for the swinging 95 movement of each striker upon its pivot.

Near each end of the carrier-plate are integral projections k^2 , formed, preferably, of the substance of the plate, and these are turned down and under the striker-arm, where they 100 serve to loosely hold the two parts, the striker-arm and the carrier-plate, in engagement. The central portion of the carrier-plate is cut away, so as to provide a place through which

the central post of the pinion may project. By this construction of the parts, the striker-arm, carrier-plate, and strikers, as above described, an extremely sensitive striking mechanism is provided, a slight rotary movement of the striker-arm being all that is necessary to throw the projecting end of the striker in contact with the lug on the inner surface of the gong.

10. In prior devices of this class in which the striker is so mounted on the striker-arm as to provide for the independent sliding as well as rotary swinging movement of the striker the sound of the bell is apt to be sluggish and 15 not clear. In my improved construction the striking mechanism is sensitive and the striker hits against the lug with a flail-like blow, rebounding from the lug freely and at once swinging outward by the operation of the centrifugal force to again strike the lug in the continued rotary movement of the striker-bar. To operate the bell, pressure is applied 20 to the outer end or thumb-piece of the lever, which causes it to swing on its pivot and move 25 the rack around in contact with the pinion on the train of gears. This causes the striker-arm to be partially rotated and the strikers to hit against the inner surface of the bell or the lug thereon. A spring secured at one end 30 to the base and at the other to the lever is put under tension by this movement of the lever, and when pressure on the thumb-piece is released reverses the rotary movement of the 35 striker-arm and rings the bell while the lever is swinging back to its normal position.

The carrier-plate and the striker-arm are preferably formed of thin metal stamped to shape, but the material of which these parts are made or their method of construction are 40 not material to the invention.

I claim as my invention—

1. In combination in a bell mechanism, a rotary striker-bar, a carrier-plate loosely mounted and having a limited sliding movement thereon, and a striker pivoted to the carrier-plate and projecting beyond the outer end thereof.
2. In combination in a bell mechanism, a rotary striker-bar, a carrier-plate loosely mounted and having a limited sliding movement thereon, a striker pivoted to the carrier-plate and projecting beyond the outer end 45 50

thereof, and stops to limit the swinging movement of the striker.

3. In combination in a bell mechanism, a 55 rotary striker-bar, a carrier-plate loosely mounted and having a limited sliding movement thereon, a striker pivoted to the carrier-plate and projecting beyond the outer end thereof, and a pin projecting through a lateral slot in the striker.

4. In combination in a bell mechanism, a rotary striker-bar, a carrier-plate loosely mounted to slide thereon, stops located on the carrier-plate and adapted to engage the 60 striker-bar, and a striker pivoted to the carrier-plate and projecting beyond the outer end thereof.

5. In combination in a bell mechanism, a rotary striker-bar, a carrier-plate loosely 65 mounted to slide thereon, an upturned lug from the striker-bar projecting through a lengthwise slot in the carrier-plate, and a striker pivoted to the carrier-plate and projecting beyond the outer end thereof.

6. In combination in a bell mechanism, a rotary striker-bar, a carrier-plate loosely 70 mounted to slide thereon, a striker pivoted to the carrier-plate and projecting beyond the outer end thereof, and an upturned lug from 75 the striker-bar, projecting through a lengthwise slot in the carrier-plate and into a lateral slot in the striker.

7. In combination in a bell mechanism, a rotary striker-bar, a carrier-plate loosely 80 mounted to slide thereon, projections from the carrier-plate adapted to embrace the striker-bar, and a striker pivoted to the carrier-plate and projecting beyond the outer end thereof.

8. In combination in a bell mechanism, a rotary striker-bar, a carrier-plate loosely 85 mounted to slide thereon, projections from the carrier-plate adapted to embrace the striker-bar, a striker pivoted to the carrier-plate, and an upturned lug from the striker-bar projecting through a lengthwise slot in the carrier-plate and into a lateral slot in the striker.

PHILIP C. ARNOLD.
